United States Patent

Des. 241,487

Patented Sept. 21, 1976

241,487

CHAIR OR THE LIKE

Charles A. Gibilterra, Granada Hills, Calif., assignor to
Vecta Group, Inc.

Continuation-in-part of abandoned design application Ser.
No. 319,626, Dec. 29, 1972. This application Dec. 30,
1974, Ser. No. 537,177

Term of patent 14 years

Int. Cl. D6—01

U.S. Cl. D6—56

Fig. 4.

Fig. 3.

FIG. 1 is a front perspective view of a chair or the like;

FIG. 2 is a side elevational view of the chair or the like;

FIG. 3 is a front elevational view of the chair or the like;

FIG. 4 is a top view of the chair or the like;

FIG. 5 is a front perspective view of the chair or the like with the seat and back shown in an alternative upholstery; and

FIG. 6 is a side elevational view of the chair or the like showing the seat and back in an alternative upholstery. (The side shown is opposite of the side shown in FIG. 2.)

The seat and back shown schematically in FIGS. 1 and 2 are continuous throughout.

This is a continuation-in-part of design application, Ser. No. D. 319,626, filed Dec. 29, 1972, and now abandoned.

I claim:

The ornamental design for a chair or the like, substantially as shown and described.
